STRIP LACE AND METHOD OF MAKING
SAME

Samuel Saftlas, Newark, N. J.

Application May 18, 1946, Serial No. 670,692

5 Claims. (Cl. 66—170)

1

This invention relates to the manufacture of knitted lace trimming and more particularly to relatively narrow strip lace of uniform width.

The principal object of the invention is to provide lace trimming of the above character more expeditiously and at less cost than has heretofore been possible.

Another object is to secure more flexibility in factory operations in the production of desired quantities of desired designs.

Other and further objects will be apparent from the following specification and claims.

In the accompanying drawings.

Fig. 1 is a fragmentary diagrammatic view showing the initial steps in the production of the lace strips;

Fig. 2 is a fragmentary similar view showing a further step;

Fig. 3 is a fragmentary diagrammatic view of one form of finished product;

Fig. 4 is a view similar to Fig. 3 showing a modified construction;

Fig. 5 is a view similar to Fig. 2 but showing an alternative arrangement; and

Fig. 6 is a fragmentary diagrammatic view showing the finished product resulting from the alternative arrangement of Fig. 5.

In carrying out my invention I knit a lace fabric in tubular form on a tubular knitting machine. As shown in Fig. 1, I knit the circular fabric 1 in a plurality of zones and lines indicated respectively at 2, 3 and 4. It will be understood that in the drawings these zones and lines are shown diagrammatically and do not indicate the actual formation of the stitches of which they are composed.

The zones 2 may be composed of any form or combination of stitches making up any desired floral or conventional lace design which the knitting machine is capable of producing. At each side of the zones 2 are formed narrow zones 3 which may or may not form part of the design. The zones 3 are composed of a plurality of any form of non-raveling or non-run stitches well known in the art. As later described the zones 3 perform two, and if desired, three functions in the completed strip.

Between adjacent zones 3 I position visually apparent vertical lines 4, shown of exaggerated width in the drawing, which are produced by repeated radially spaced stitch formations in the knitting courses, such as omitting one or more needles or dropping one or more stitches. The sole function of the lines 4 is to form a guide along which the tubular fabric may be cut, as

2

shown at 5 in Fig. 2, into strips generally indicated at 6. Lines 4 preferably are made as narrow as is consistent with this function and within the tolerances required by the cutting practice followed in severing the tube into strips.

After the cutting operation the cut edges of the strips 6 are bound or furnished, as shown in Fig. 3, by overseaming as indicated at 7 using any conventional type of overseaming sewing machine. The non-curling character of the non-run stitches of which zone 3 is composed permits easy manipulation of the strips in the overseaming machine. Furthermore the solidity of the fabric in the zone 3 serves to reinforce the edge of the lace strips, permitting the threads of the more open stitches of the design zone 2 to readily adjust themselves to a flat condition. If desired, and as shown in Fig. 3, the zones 3 may be made sufficiently wide to form a part of the design and give a stripe effect at the edges of the strip. The zones 3 may however be narrowed so as to be nearly covered by the over seams 7 so that the appearance is merely that of a finished edge on the body of the strip, without sacrificing the two functions of the zones 3 previously described. In any case the cut threads are anchored in the zones 3 by the machine stitching and the free thread ends along the lines 4 are bent and matted against the edges of the zones 3 by the threads 20 of the overseam 7 so as to be covered thereby. The lines 4 as such, thus disappear from the finished strip, but the free ends of the threads along the lines 4 when confined by the overseam 7 may give some added bulk and strength to the edges of the finished strip.

Where the stitches forming zone 3 are sufficiently tight and compact, the edges of the cut strips may be adequately held by running a conventional "Singer" stitch 8 through the zones 3 40 as shown in Fig. 4. The resulting product has a much less "finished" appearance, but is somewhat cheaper to make and is satisfactory for some purposes. The overseamed edge 7 of Fig. 3 is preferable.

As above pointed out the function of the line 4 is to provide a guide for cutting the tubular fabric into strips of uniform width and is desirably made as narrow as possible as by omitting a single needle or dropping a single stitch. In practice, 50 where the body of the lace design consists of a repetitious overall pattern with overlapping design areas formed wholly or in substantial part of non-run types of stitches, the lines 4 may comprise observable longitudinal lines formed by 55 repeated points in the overall pattern, formed by

dropped stitches or otherwise, which are positioned vertically above each other in succeeding knitting courses. For example as diagrammatically illustrated in Fig. 5 the tubular fabric 1 may be knit in an overall pattern comprising overlapping areas such as lunes 9 formed of non-run types of stitches the space between the areas 9 being formed of open stitch areas 10. In such a design radially and vertically repeated points 11 are provided to form guide lines, indicated by the arrows 12, equivalent in their guiding function to the lines 4. When the tubular fabric is cut into strips 13 along the lines 12, as shown in Fig. 6, the cut edges comprise non-run edge portions 14 where the areas 9 have been cut through, separated by spaces 15 where the areas 10 have been crossed by the cutter. When the edges of the so cut strip are provided with an overseam 16 the edge portions 14 of the cut areas 9 form zones in which, although interrupted by the spaces 15, the cut lace forming threads are anchored in the same manner as in the continuous zones 3 previously described. Where the over seam 16 crosses the open spaces 15 I find that the overseaming threads form a chain 17 which is self sustaining and forms with the overseamed edges of the portions 14 a continuous finished edge for the strip.

I am aware that circular, uniformly knit textile fabrics have been cut longitudinally and that fringed edges have been provided for such textile fabrics by dropping a multiplicity of stitches, through which a cut is made in forming the fringe. The knit lace as distinguished from a uniform textile presents a quite different material both from the standpoint of manufacture and handling. While the desirability of inexpensive lace strips has been recognized the art has directed its efforts to attempting to reduce the cost of narrow web knitting in general. By my invention it is possible to get a substantial production of strip lace of a given design from a single circular knitting machine and the proportion of different designs or different widths of strip lace produced is made extremely flexible since a relatively small number of knitting machines may be kept in substantially continuous production and, with easily and quickly made adjustments, produce a large or small quantity of strip lace in a wide range of designs and widths. This is important particularly in small plants and is accomplished by the design versatility of the circular knitting machine, in forming the body design of the lace strips, in combination with non-run edge zones, interrupted or continuous, the provision of a cutting guide line in the circular knitting sequence, and the overseaming finishing of the edge. The advantageous flexibility resulting from my invention is further illustrated by the fact that while the form of Figs. 1, 2 and 3 give a practically unlimited range in design, the form of Figs. 5 and 6 while more limited in the range of design makes possible extremely economical production of strip lace in varying widths. A further advantage of the lace strips made in accordance with my invention resides in the fact that they have the surface directed flexibility in all directions which is characteristic of circular knit lace and which not only permits the cut strips to adjust themselves to a plane but permits the strips to be applied to curved edges and to be pressed flat in curved form, the necessary adjustment of the

stitches taking place without objectionable deformation of the lace fabric. When used as insertions or as applique in table cloths, drapes and the like, the strip lace of my invention achieves 5 remarkably rich appearing results at exceedingly low cost which substantially extends the field of use and enjoyment of such articles.

What I claim is:

1. Strip lace which comprises a flat width of circularly knit lace fabric, the body of the strip being knit in a predetermined lace design pattern, the edge portions of the strip being formed in substantial part at least by non-run knit stitches, lace-forming threads presenting free ends at the edges of said non-run edge portions, said free ends being anchored in said portions by machine stitching.
2. Strip lace which comprises a flat width of circularly knit lace fabric, the body of the strip being knit in a predetermined lace design pattern, the edge portions of the strip being formed in substantial part at least by non-run knit stitches, the lace-forming threads presenting free ends at the edges of said non-run edge portions, 20 said free ends being anchored in said portions by over-seam machine stitching forming a continuous finish at the edges of the strip.
3. The method of making strip lace which comprises knitting a circular lace fabric of predetermined design, said design including radially spaced stitch formations forming visually apparent vertical guide lines by which the circular fabric may be cut longitudinally into strips of desired uniform width, the portions of the fabric 30 adjacent said lines being formed in substantial part at least by non-run stitches, severing said fabric into strips along said lines to locate the cut ends of the lace-forming threads at said non-run stitch portions of the edges of the strip, and 35 running a seam of machine stitching along the edge portions of the severed strips closely adjacent the edges thereof to anchor the cut lace-forming threads in said non-run edge portions.
4. The method of making strip lace which comprises knitting a circular lace fabric in a radially repeated strip design, dropping at least one stitch between each such radially spaced strip design in each knitting course to form visually apparent vertical guide lines by which the circular fabric may be cut longitudinally into strips of predetermined uniform width the portions of the fabric adjacent said lines being formed in substantial part at least by non-run stitches, 45 severing said fabric into strips along said lines, and overseaming the edge portions of the strip to anchor the cut lace-forming threads in said non-run edge portions and provide finished edges for the strips.
5. The method of making strip lace which 50 comprises knitting a circular lace fabric in a radially repeated strip design, providing radially spaced stitch formations in each knitting course to form spaced visually apparent guide lines longitudinally of the fabric by which the circular fabric may be cut into strips of uniform width, the portions of the fabric adjacent said lines being formed in substantial part at least by non-run stitches, severing said fabric into strips along said lines, and over-seaming the edge portions 55 of the strip to anchor the cut lace-forming threads in said non-run edge portions and provide finished edges for the strips.
6. The method of making strip lace which 60 comprises knitting a circular lace fabric in a radially repeated strip design, providing radially spaced stitch formations in each knitting course to form spaced visually apparent guide lines longitudinally of the fabric by which the circular fabric may be cut into strips of uniform width the portions of the fabric adjacent said lines being formed in substantial part at least by non-run stitches, severing said fabric into strips along said lines, and overseaming the edge portions of the strip to anchor the cut lace-forming threads in said non-run edge portions and provide finished edges for the strips.
7. The method of making strip lace which 65 comprises knitting a circular lace fabric in a radially repeated strip design, providing radially spaced stitch formations in each knitting course to form spaced visually apparent guide lines longitudinally of the fabric by which the circular fabric may be cut into strips of uniform width, the portions of the fabric adjacent said lines being formed in substantial part at least by non-run stitches, severing said fabric into strips along said lines, and over-seaming the edge portions 70 of the strip to anchor the cut lace-forming threads in said non-run edge portions and provide finished edges for the strips.

SAMUEL SAFTLAS.
